[57] **CLAIM**

The ornamental design for a power/data module, as shown and described.

DESCRIPTION

FIG. 1 is an isometric view of a power/data module incorporating my new design;
FIG. 2 is a top plan view thereof;
FIG. 3 is a side elevation view thereof;
FIG. 4 is an end elevation view thereof;
FIG. 5 is a rear elevation view thereof;
FIG. 6 is an isometric view thereof similar to FIG. 1, showing the power/data module in an open position;
FIG. 7 is a top plan view of the module in its open position of FIG. 6;
FIG. 8 is a front elevation view of the module in its open position;
FIG. 9 is a rear elevation view of the module in its open position; and,
FIG. 10 is a side elevation view of the module in its open position.
The broken lines showing a flat surface in FIGS. 1, 3-6 and 10 and the outer walls of the module in FIGS. 1, 3, 4, and 6-10 and the plug sockets in FIG. 6, are for illustrative purposes only and form no part of the claimed design.
